HERMAN L. VAN VALKENBURG, OF WAUWATOSA, WISCONSIN, ASSIGNOR TO INDUSTRIAL CONTROLLER CO., OF MILWAUKEE, WISCONSIN, A CORPORATION OF WISCONSIN.

ELECTRIC SWITCH.

Application filed March 28, 1927. Serial No. 178,984.

This invention relates to improvements in electric switches.

It is one of the objects of the present invention to provide an electric switch having a quick make and break contact, in which a comparatively strong pressure is maintained on the contact fingers up to the instant of the make or break of the contact.

A further object of the invention is to provide an electric switch combined with a toggle mechanism and a spring, in a manner to secure comparatively a strong contact pressure without the use of a strong spring.

A further object of the invention is to provide an electric switch which while particularly, although not solely, adapted for use as a float switch, may be used wherever a quick make and break switch is desired.

A further object of the invention is to provide an electric switch of the quick make and break type which is adapted to carry comparatively heavy currents.

A further object of the invention is to provide an electric switch which while permitting a very slow movement of its controlling arm, will cause the switch contacts to move with a quick positive movement in making or breaking electrical contacts.

A further object of the invention is to provide an electric switch which is of simple construction, is strong and durable, and is well adapted for the purpose described.

With the above and other objects in view, the invention consists of the improved electric switch and its parts and combinations as set forth in the claims and all equivalents thereof.

In the accompanying drawing in which the same reference characters indicate the same parts in all of the views:

Fig. 1 is a side view of the improved electric switch, the cover being removed to show interior construction;

Fig. 2 is a vertical sectional view thereof taken on line 2—2 of Fig. 1, and showing the switch in closed position.

Fig. 3 is a view similar to Fig. 2 with the switch shown in open position;

Fig. 4 is a horizontal sectional view taken on line 4—4 of Fig. 1, parts broken away; and

Fig. 5 is a sectional detail view showing the parts in another position.

Referring to the drawings, the numeral 8 indicates a frame or rectangular casing having a side opening closed by a cover 9 which

is removably secured to the casing by screws 10. The casing is provided with lugs 11 for attaching it to a support as desired. One of the inner walls of the casing is formed with projecting portions 12 to which a slate or other insulating panel 13 is connected by screws 14. Two spaced fixed contacts 15 are mounted on the face of the panel by countersunk screws 16, and wire terminals 17 are connected to the fixed contacts by screws 18. A U-shaped bracket 19 is mounted rigidly on the panel 13 and its arms 19' extend outwardly therefrom and carry comparatively a long shaft 20 and a short shaft 21, the short shaft being outermost from the panel. A switch arm bell crank member 22 is journaled on the short shaft 21 between the two outermost arms 19' and carries a transverse insulating bar 23 to which the angular portions of spaced yielding two part switch fingers 24 are connected. The yielding portions 24' of the switch fingers are positioned to engage and form an electrical contact with the fixed contacts 15 when in their "on" position. Said yielding portions are loosely, pivotally connected to the other portions of the fingers 24 by screws 25, which are threaded through the inner end portions of the parts 24' and extend loosely through the non-yielding portions of the fingers 24. Headed pins 26 extending loosely through both portions of the contact fingers are encircled by springs 27 which are interposed between the parts 24' and caps 28 mounted on the outer ends of the pins 27. As thus constructed, the springs 27 will normally hold the portions 24' yielding against the other portions, and in moving into engagement with the fixed contacts 15, the springs will permit greater movement inwardly of the non-yielding portions of the fingers 24 than the yielding portions 24' and increase the spring tension of said yielding portions. The pivot screws 25 also extend through U-shaped clamping members 29 to clamp end portions of pig tail leads 30 extending between the U-shaped members and the yielding portions of the fingers 24, as clearly shown in Fig. 5. The opposite ends of the pig tail leads 30 are connected to wire terminals 31 mounted on the insulating panel 13 opposite to the end upon which the terminals 17 are mounted. The end portion of the casing 9 adjacent the terminals 31 is provided with a threaded opening 32 through which the circuit wires (not shown) extend 110

for connection with the terminals 17 and 31. If desired, the wires may extend through a tubular conduit (not shown) which may be threaded into the opening 32.

5 An angular lever 33 medially fulcrumed on the long shaft 20 has one of its arms extending towards the switch arm bell crank lever member 22 and is pivotally connected thereto by a short toggle link 34, forming a 10 toggle joint connection between the angular lever 33 and the bell crank lever member 22. As thus formed, the axis of the pivotal connection between the lever 33 and the bell crank lever 22, in moving from one position 15 to the other, will travel in an arc intersecting an imaginary line between the fulcra of the levers 33 and 22 and of course will not move the switch arm until the axis of the pivotal connection mentioned swings to one or the 20 other side of said imaginary line thus providing a quick positive movement of the switch arm. The other or longer arm 33' of the angular lever 33 extends at an angle towards one side edge of the slate and is notched 25 to receive one of the looped ends of a coiled spring 35. The other looped end of the coiled spring 35 is hooked over the notched end portion of a cranked arm 36 having a shaft 30 portion 38 which extends through and is journaled in one side portion of the casing 8.

The axis of the cranked arm 36 is so positioned with relation to the arc of movement of the lever part 33' that the coiled spring 35 will be swung over the plane of the axis of 35 the long shaft 20, so that in turning, the lever 33' will not be moved until the axis of the coiled spring 35 swings over the plane of the axis of the long shaft 20, and when this occurs, the lever 33 will be moved with a quick, 40 positive movement. The said movement will at the same time move the axis of the link and lever pivot over the imaginary line before mentioned and cause the switch contacts 24 to be also moved with a similar quick 45 movement, and open or close the circuit with a snap. Stop screws 39 limit the movement of the cranked arm 36 in both directions, while the angular lever 33 is limited in its movement by portions of the lever striking 50 against the portion of the U-shaped bracket bearing on the panel 13. Particular attention is directed to the fact that the swinging of the spring 35 over the fulcrum 20 before there is any movement of the link 34 and the 55 movement of said link axis over the imaginary line before switch arms are moved provides for maintaining the tension on the switch arms up to the instant they are moved, and then moving the arms with a quick positive 60 movement regardless of the slowness of the movement of the controlling means now about to be described.

The cranked arm shaft 38 at its outer end has mounted fast thereon a double arm 40 65 formed with bifurcated end portions 40' for

engagement with a chain or other means 41 which is adapted to extend above and around the upper portion of the casing, as indicated in Fig. 2. Idle guide pulleys 42 mounted on the upper portion of the casing 8 guide 70 and support the said chain. The chain at one end may be connected to a float 43 extending into a tank 44 and the other end of the chain is connected to a counterweight 45 to partly counterbalance the float to permit the 75 level of the water in the tank to control the movement of the chain. The chain extends freely between the end bifurcations of the double arm and is maintained in position with relation thereto by transverse pins 46. Engaging members 47 adjustably clamped to the chain beneath the ends 40' of the arms are positioned to engage said ends and move the double arm to actuate the switch. 80

As the coiled spring is put under considerable tension when the parts are moved to actuate the movable contacts, the contacts will be held firmly together until the circuit is broken and in breaking the movement will be accomplished very quickly with a snap. 90 The same movements in reverse order will occur in making electrical contact between the contacts.

From the foregoing description, it will be seen that the electric switch is of very simple 95 construction and is well adapted for the purpose described.

What I claim as my invention is:

1. An electric switch, comprising a frame, an insulating member connected thereto, a bracket connected to the insulating member, a lever member fulcrumed on the bracket and having two arms, a movable switch contact fulcrumed on the bracket and having a toggle and pivotal connection with one of the arms 100 of the lever member, a fixed contact mounted on the insulating member and engaged by the movable contact, terminals mounted on the insulating member and connected to the contacts, a cranked arm journaled in the 105 frame, a yielding means connected to the cranked arm and to the other arm of the lever member and positioned to swing transversely across the plane of the axis of the lever member fulcrum to actuate the movable contact 110 with a quick positive movement, and means for rocking the cranked arm. 115

2. An electric switch, comprising a frame, an insulating member connected thereto, a bracket connected to the insulating member, a fixed contact mounted on the insulating member, a lever member fulcrumed on the bracket and having two arms one of which extends to one side of the insulating member, a movable switch contact fulcrumed on the bracket and having a toggle and pivotal connection with one of the arms of the lever member and movable to engage the fixed contact, terminals mounted on the insulating member and connected to the contacts, a 120

cranked arm journaled in the frame, a coiled spring connected to the cranked arm and to the extending other arm of the lever member and positioned to swing transversely across the plane of the axis of the lever member fulcrum to actuate the movable member with a quick positive movement, and means for rocking the cranked arm.

3. An electric switch, comprising a frame, an insulating member connected thereto, a bracket connected to the insulating member, fixed contacts mounted on the insulating member, a lever member fulcrumed on the bracket and having two arms, one of which extends to one side of the fulcrum of the lever member, movable switch contacts fulcrumed on the bracket and having a toggle and pivotal connection with one of the arms of the lever member and movable to engage the fixed contacts, terminals mounted on the insulating member and connected to the movable and the fixed contacts, a cranked arm journaled in the frame and extending to a point on the opposite side of the fulcrum of the lever member to that of the extending arm of the lever member, a coiled spring connected to the cranked arm and to the extending arm of the lever member and arranged to swing transversely across the plane of the axis of the lever member fulcrum to actuate the movable member with a quick positive movement, and means for rocking the cranked arm.

4. An electric switch, comprising a casing, an insulating member mounted therein, a bracket mounted on the insulating member, fixed contacts mounted on the insulating member, a lever member fulcrumed on the bracket and having two arms, one of which extends to one side of the fulcrum of the lever member, movable switch contacts yieldingly fulcrumed on the bracket, a toggle link pivotally connecting the movable switch contacts to the arm of the lever member other than the arm extending to one side of the lever fulcrum, and arranged to have its pivotal connection with the lever member swing to opposite sides of an imaginary line between the fulcras of the switches and the lever member, terminals mounted on the insulating member and connected to the movable and fixed contacts, a cranked arm extending through and journaled in the casing and having a portion on the opposite side of the fulcrum of the lever member to that of the extending arm of the lever member, a coiled spring connected to the cranked arm and to the extending arm of the lever member and arranged to swing transversely across the plane of the axis of the lever member fulcrum to actuate the movable member with a quick positive movement, and means for rocking the cranked arm.

quick positive movement, and means for rocking the cranked arm.

5. An electric switch, comprising a casing, an insulating panel mounted therein, a U-shaped bracket mounted on the panel, pairs of fixed contacts mounted on the panel, a lever member fulcrumed on the bracket and having two arms, one of which extends to one side of the fulcrum of the lever member, two part movable switch contacts yieldingly fulcrumed on the bracket, a toggle link pivotally connecting the movable switch contacts to the arm of the lever member other than the arm which extends to one side of the lever fulcrum, and arranged to have its pivotal connection with the lever member swing to opposite sides of an imaginary line between the fulcras of the switches and the lever member, terminals mounted on the insulating member and connected to the fixed and movable contacts, some of said terminals having flexible connections with the yielding portions of the movable contacts, a cranked arm extending through and journaled in the casing and having a portion on the opposite side of the fulcrum of the lever member to that of the extending arm of the lever member, a coiled spring connected to the cranked arm and to the extending arm of the lever member and arranged to swing transversely across the plane of the axis of the lever member fulcrum to actuate the movable member with a quick positive movement, and means for rocking the cranked arm.

6. An electric switch, comprising an insulating support, a pair of fixed contacts mounted thereon, a pair of two part contacts pivotally mounted on the support and movable to engage the fixed contacts, a lever member pivotally mounted on the support and having a toggle link connection with the movable contacts and an arm projecting to one side of the pivotal connection of the lever member with the support, said toggle link having its pivotal connection with the lever member swing to opposite sides of an imaginary line between the fulcras of the switches and the lever member, a cranked arm journaled on the support and having its cranked portion extending on the side of the pivotal connection of the lever member opposite to the projecting arm, a spring connected to the cranked arm and to the projecting arm of the lever member and arranged to swing transversely across the plane of the axis of the lever member with a quick positive movement, and means for rocking the cranked arm.

In testimony whereof, I affix my signature.

HERMAN L. VAN VALKENBURG.
